(57) **CLAIM**

The ornamental design for a vehicle wheel, toy vehicle wheel, and/or replicas thereof as shown and described.

DESCRIPTION

This application contains subject matter related to the following co-pending U.S. design patent applications:

Application Ser. No. 29/858,122, filed Oct. 28, 2022 and entitled “Vehicle Wheel, Toy Vehicle Wheel, and/or Replicas Thereof;”

Application Ser. No. 29/912,630, filed Sep. 21, 2023 and entitled “Vehicle Wheel, Toy Vehicle Wheel, and/or Replicas Thereof;”

Application Ser. No. 29/925,780, filed Jan. 26, 2024 and entitled “Vehicle Wheel, Toy Vehicle Wheel, and/or Replicas Thereof;” and

Application Ser. No. 29/886,902, filed Mar. 15, 2023 and entitled “Vehicle Wheel, Toy Vehicle Wheel, and/or Replicas Thereof.”

FIG. 1 is a perspective view of a vehicle wheel, toy vehicle wheel, and/or replicas thereof according to the design;

FIG. 2 is an additional perspective view thereof;

FIG. 3 is an additional perspective view thereof;

FIG. 4 is a front elevation view thereof; and,

FIG. 5 is a side elevation view thereof.
